UNITED STATES PATENT OFFICE

127,270

DESIGN FOR A PAIR OF SPECTACLES

James W. Engler, Atlanta, Ga.

Application December 26, 1940, Serial No. 97,613

Term of patent 14 years

To all whom it may concern:

Be it known that I, James W. Engler, a citizen of the United States and resident of Atlanta, county of Fulton, State of Georgia, have invented a new, original, and ornamental Design for a Pair of Spectacles, of which the following is a specification, reference being had to the accompanying drawing, forming part thereof.

Fig. 1 is a front view of the pair of spectacles, showing my new design;

Fig. 2 is a plan view of the same;

Fig. 3 is a side view, the temple being broken away for convenience of illustration; and

Fig. 4 is a perspective view on an enlarged scale of one of the lenses and the temple mounting in order to bring out more clearly the details of the same.

My design for a pair of spectacles is characterized by the configuration of the temple mounting in combination with the placement of the same on a pair of spectacles as illustrated.

I claim:

The ornamental design for a pair of spectacles, substantially as shown and described.

J. W. ENGLER.
